METHOD AND MECHANISM FOR TREATING
FILAMENTS OR FIBERS

Benjamin F. McCreery, Glens Falls, N. Y.

Application February 7, 1942, Serial No. 429,906

3 Claims.

(Cl. 28—1)

My invention relates to a new and improved method and to a new and improved mechanism for treating various types of filaments or fibers, such as "nylon" filament or fiber, and, more particularly, for treating waste "nylon" filament or fiber or yarn or "nylon" material in other form. The invention includes the treatment of all stretchable fibers or filaments.

One of the objects of the invention is to provide a simple and efficient and labor-saving method of stretching "nylon" filament material and the like, and to minimize the loss of said material.

Another object of the invention is to provide a method for making a filament or yarn which is sufficiently soft and non-wiry so that said filament or yarn can be used for making soft woven fabric, and for other purposes.

Other objects of the invention will be set forth in the annexed description and drawings, which illustrate a preferred embodiment thereof, it being understood that the above statement of the objects of my invention is intended generally to explain the same without limiting it in any manner.

Fig. 1 is a side elevation of the improved machine, which is used for practicing the improved method. This elevation is taken at the right-hand side of Fig. 2.

Fig. 2 is a top plan view of Fig. 1.

Fig. 3 is another side elevation, taken at the left-hand side of Fig. 2.

Fig. 4 is a sectional view on the line 4—4 of Fig. 2.

Fig. 5 is a detail enlarged sectional view, illustrating the pronged or porcupine feed roll which is used in various parts of the apparatus.

Fig. 6 is a detail perspective view of one of the teeth which is used on the main drum of the apparatus.

The designation "nylon" is applied to synthetic fiber-forming polymeric amides, which have a protein-like chemical structure. The method of producing such "nylon" material is disclosed in U. S. Patent No. 2,130,948, and in various other patents. In making a "nylon" filament, the material is extruded and the extruded filament is given a fairly high twist, which remains in the final filament which is supplied to the knitting industry. The "nylon" yarn which is made with the use of such filament, is stiff and resilient, and such yarn has a wiry feel, so that such yarn is not suitable for making a soft woven fabric. Therefore, the use of "nylon" yarn has been con-

fined exclusively, or almost exclusively, to the knitting industry.

In the process of making "nylon" yarn by extrusion, there is a great deal of waste because the extruded filament breaks between the point of extrusion and the point at which the twist is given to the extruded filament. It is a particular object of my invention to treat said waste "nylon" filament, so that it can be made into a yarn which can be used for making knitted or woven fabrics.

The machine is provided with a frame F, in which a shaft 1 is turnably mounted. A drum 2, which has reinforcing ribs 3, is keyed to the shaft 1, so that the drum 2 and the shaft 1 turn in unison.

As particularly shown in Fig. 3, a gear 4 is keyed to the shaft 1. This gear 4 meshes with a smaller gear 5, which is keyed to the shaft keyed to 6. Said gear 5 meshes with a smaller gear 7, which is keyed to the shaft 8. As shown particularly in Fig. 2, the shaft 8 is keyed to a grooved pulley 9, which is driven by means of a corresponding and smaller grooved pulley 10, which is keyed to the shaft of an electric motor 11. The grooves of the pulleys 9 and 10 are connected by a series of V-belts 12.

The outer wall of drum 2 can be made of any suitable rigid material, which is assembled with the core of said drum 2. The ribs 3 are integral with the radial arms R of said core, and non-integral with said outer wall.

Any other suitable type of speed-reducing mechanism can be used for rotating the drum 2 at regulated speed, which is about 125 revolutions per minute. Whenever I state any figures by way of specific example, the invention is not limited thereto.

As shown particularly in Fig. 4, the outer wall of the drum 2 is provided with a series of recesses. Each recess has a radial planar wall 14 and a convex wall 15. Each convex wall 15 is located between a pair of successive radial walls 14. Each recess is of varying radial depth, its depth being the greatest at its radial base, namely, at its respective radial wall 14.

A transverse bar 16 is fixed to each radial wall 14, by means of screws 17, or other suitable fastening members, which extend through holes 18 of the respective bars 16. Each bar 16 is provided with a series of tangential teeth 19. The teeth 19 of each series or set are perpendicular to the respective planar radial wall 14. As shown particularly in Fig. 6, each tooth 19 is of rectangular cross-section and it has a tapered point 19a. The wide planar faces of each set of teeth 19 are

parallel to each other. The thickness of each pin 19 is about $\frac{1}{8}$ of an inch and the width of its wide face is about $\frac{1}{4}$ of an inch. The total exposed length of each pin 19 is about $1\frac{1}{2}$ inches. The spacing between adjacent teeth 19 of each set or series, is about $\frac{1}{4}$ of an inch. This close spacing is not shown in Fig. 2, because for convenience, the representations of some of the teeth 19 have been omitted in Fig. 2.

Each pin 19 has a removable drive fit in its bar 16, so that a tooth 19 can be readily removed and replaced, if it becomes broken or otherwise defective.

As shown particularly in Fig. 1, the machine is provided with a table T, on which the "nylon" waste N is laid by the operator. The "nylon" waste is fed forwardly off the table T, by a pair of feed rolls 20 and 21. These feed rolls 20 and 21 can have cores of any rigid material, and said cores are provided with resilient outer sleeves S, which are made of vulcanized rubber or the like. Said rolls can be made throughout of cast iron or other rigid material, with corrugated peripheries, said corrugations being perpendicular to the parallel axes of said rolls. As shown in Fig. 1, the shaft of the lower feed roll 21 is positively driven by means of a chain 22, which meshes with a sprocket on the shaft of the lower feed roll 21, and with a corresponding sprocket on the shaft 23 of the lower porcupine feed roll 24. The shafts of the feed rolls 21 and 24, and the other shafts of the machine, with the exception of the shaft of the motor 11, are suitably journaled in the frame F.

The shaft 25 of the upper feed roll 20 is provided with the conventional slide block, which can slide up and down in the guide frame 26, which is fixed to or which is integral with the frame F. The usual compression spring 27 downwardly urges the slide block of the shaft 25, so that the sleeves S of the feed rolls 20 and 21, are maintained resiliently in contact, under suitable regulated pressure.

The "nylon" waste N is thus compressed into the form of a thin web by the feed rolls 20 and 21, and said web is fed forwardly by said feed rolls 20 and 21, between the bottom porcupine roll 24 and the associated top porcupine roll 28. The web can be stretched to some extent, which is less than the maximum stretching to which the material is subjected in the machine, anterior the feed rolls 20 and 21. The material can be supplied to the feed rolls 20 and 21, by any suitable endless feed belt.

As shown more particularly in Figs. 1 and 4, the upper porcupine roll 28 has a shaft 29. A sprocket is keyed to said shaft 29, and said sprocket is connected to a chain 30 to a companion sprocket which is keyed to the shaft 31. A gear 32 is keyed to the shaft 31, and said gear 32 meshes with a gear 33, which is keyed to the shaft 1 of the drum. As shown more particularly in Fig. 3, a gear 34 is keyed to the shaft 29, and said gear 34 meshes with a gear 35, which is keyed to the shaft 23 of the lower porcupine feed roll 24. The porcupine feed rolls 28 and 24 are thus driven equally and in unison.

As shown more particularly in Figs. 1 and 3, a third porcupine feed roll 36 is keyed to a shaft 37. The shafts 31 and 29 are provided with respective sprockets, which are connected by means of a chain 38, thus positively driving the third porcupine feed roll 36. The three porcupine feed rolls 24, 28 and 36 are thus rotated in unison at the same speed, and said three porcupine feed

rolls have the same effective or pitch diameter. Any number of porcupine feed rolls can be utilized, but the use of three porcupine feed rolls is sufficient.

5 The smooth feed rolls 20 and 21 and the porcupine feed rolls 24 and 28 are thus rotated at the same angular speed. However, the effective diameter of each of the porcupine feed rolls 28 and 24 is much greater than the effective diameter of the feed rolls 20 and 21. Therefore, the material is subjected to stretching by the porcupine feed rolls 28 and 24. This stretch may be any desired percentage of the total or maximum stretch which is imparted to the material by the complete machine. The stretch which is effected by said porcupine feed rolls 28 and 24 may be less than or more than 50% of said total stretch, or 50% of said total stretch.

Some of this total stretch may be produced by 20 the third porcupine feed roll 36. This stretch is produced by the respective porcupine feed rolls, because the pins of such porcupine feed rolls are moved forwardly, at greater linear speed than the regulated forward linear speed of the material. 25 The forward linear speed of the material is regulated by the feed rolls 20 and 21. The pins of the porcupine rolls exert frictional forward force upon the material, thus stretching the material.

It is desirable to take out all, or almost all, of 30 the stretch of the "nylon" waste by the machine, so that the waste which is accumulated in the form of a web on the recessed periphery of the drum 2, has little or no remaining stretch, when said web is removed from said drum 2.

35 As shown in detail in Fig. 5, each porcupine feed roll is provided with curved teeth 39. The teeth 39 are arranged in pairs, each pair having a common base 40. The bases 40 are embedded in a flexible surface layer 41, made of leather or 40 vulcanized rubber or the like, and said surface layer 41 is suitably fixed to the core C of the respective porcupine feed roll. The diameter of the drum 2 may be from 30-36 inches, and, as previously stated, the invention is not limited to any specific dimensions or other specific figures which are stated herein. The web of stretched material which is delivered to the first set of pins 19, namely, the set which first contacts with the material which is fed forwardly by the porcupine 45 feed rolls 28 and 24, is gripped between the teeth of said set, and said web is carried around the recessed periphery of the drum 2. The "nylon" waste is collected in the spaces between the pins 19, and the drum 2 and its pins 19 subject the "nylon" material to its final or maximum stretch, so that the web of "nylon" material which is finally taken off the drum 2, has little or no residual stretch. The respective directions of rotation of the drum 2 and of the feed rolls, are indicated by the respective arrows in Fig. 4. The drum 2 rotates counterclockwise. The "nylon" filaments are thus laid parallel to each other in the spaces between adjacent teeth 19 of each set or series. After a web 42 of sufficient thickness has 50 been accumulated upon the periphery of drum 2, said web is removed and cut into staples of any desired length. Said web can be cut in a direction parallel to the axis of drum 2, in order to remove it from the drum 2. The rotation of the drum 2 and the operation of the machine is 55 stopped, in order to remove the web 42. These staples are then spun into yarn by conventional methods and machinery.

When the web 42 has been built up to its final thickness upon the drum 2, the tapered points

19a of the pins 19 project beyond the respective adjacent portions of the web, to a distance of about $\frac{1}{4}$ of an inch. While the web is thus being formed upon the drum 2, and in the final form of said web, the outer wall of said web 42 has a recessed shape, as indicated in Fig. 4.

The arrangement of the pins which has been described, is useful in preventing premature breakage of said pins, and in providing a proper and even stretching action upon the filaments of "nylon" waste.

Brushes B and Ba are provided with bristles which are mounted upon suitable rolls, which have respective shafts 43 and 44.

As shown more particularly in Fig. 1, the shaft 43 has a sprocket which is connected by a chain 45 to another sprocket which is keyed to the shaft 1. Likewise, the shaft 44 has a sprocket which is connected by a chain 46 to another sprocket which is keyed to the shaft 1. The brushes B and Ba are therefore positively driven, in order to brush off any material which clings to the pins 39 of the porcupine feed rolls 28 and 36. The brushes B and Ba can be located to brush the points of pins 19, or additional brush means can be provided to cleanse the points of pins 19.

As shown more particularly in Fig. 4, the teeth 39 are of curved or convexo-concave shape, and their concave faces are moved in the same directions as the material which is engaged by said teeth.

Each of the curved teeth 39 may be aligned with a space between a pair of teeth 19. Each of said teeth 19 may be aligned with a respective tooth 39.

The feed rolls 20 and 21 feed a thin web of the material N forwardly. The front end of said web is engaged by the teeth of the lower porcupine roll 24, and said front end is thus fed between the teeth of the superposed porcupine rolls 28 and 24. These porcupine rolls feed the front end of the web into a position in which said front end is engaged by a set of the teeth 19, which feed the front end of the web in unison with the periphery of the drum 2. A web of increasing thickness is thus built up on the periphery of the drum 2. Said web extends across the respective sets of pins 19. The pins 19 stretch the filaments of the web and also arrange said stretched filaments parallel to each other. When the web on the drum 2 is of the desired thickness, the operation of the machine is stopped. The operator then cuts the web along a single transverse line, and then starts the machine so as to turn the drum. The operator continues to cut the web along spaced transverse lines, so as to cut the filaments into staples of any desired length until the entire quilt has been removed from the drum 2. The drum 2 may be stopped during each cutting operation.

After the web has been removed, the machine is ready for another run.

A substantial part of the web on the drum 2 is located in the spaces between the teeth 19.

Each circumferential row of the teeth 39 of the rolls 28 and 24 may be circumferentially aligned with a circumferential row of teeth 19, so that each plane which is perpendicular to shaft 1, and which has a circumferential row of teeth 19, has two circumferential rows of teeth 39 of rolls 28 and 24, and a third circumferential row of teeth 39 of the auxiliary porcupine roll 36.

The recessed formation of the drum 2 is advantageous, because the filaments are stretched

over a series of spaced walls. It will be noted that the material is stretched and accumulated upon the drum 2, without the use of radial pressure.

The invention covers numerous sub-combinations, as well as the complete combination disclosed herein, and it also includes the recessed formation of the drum 2, as a novel part or element.

The convex wall 15 of each recess is designated as its peripheral wall. Referring to Fig. 4, the deep end of each recess is designated as its rear end. Hence, the depth of each recess increases successively from its front end to its rear end and the pins 19 project forwardly. The pins 19 are connected to their respective recesses at the respective rear ends of said recesses. Each pin 19 is spaced from its respective peripheral wall 15. The front end of each recess is preferably at the rear end of the next succeeding recess. Each pin 19 is located wholly in its respective recess. That is, the length of a radial line between the axis of the shaft 1, and the point of a tip 19a, is substantially equal to the length of a radial line from said axis of rotation to the outer end of the respective wall 15.

The representation of the drum 2 in Fig. 4 is substantially to scale, and reference is made thereto for further details. The drum 2 is rotated at a peripheral speed which exceeds the feeding speed of the rolls 21 and 20, and which also exceeds the feeding speed of the porcupine rolls 28 and 24, to the extent of the feeding action of said porcupine rolls 28 and 24. The speed at which the material is fed forwardly to the drum, is controlled primarily, and even wholly, by the feeding rolls 20 and 21. While each strand is wound substantially in spiral form, each said strand is preferably formed with a series of separated humps at the deep ends of the respective recesses.

The machine stretches the filaments so as to eliminate or minimize knobs or beads on the filaments. This is highly important, because the staples can be spun into yarn as fine as No. 90 and even finer, in the silk system. The steady and uniform stretching prevents breakage of the filaments, so that the cut staples are of uniform length, thus greatly lowering the expense of spinning the staples into yarn. Since the staples are of uniform length, the formation of knots in the spinning operation is eliminated, thus greatly lowering the cost of finishing.

Fig. 4 shows that the web which is spirally wound on the drum, has ten web-sections. If the drum 2 were of polygonal shape, having ten equal peripheral walls, the change in angle between adjacent sections would be only 36° . However, by forming and maintaining each web-section so that it is thicker at its rear end than at its front end, the angle at the junction between adjacent web-sections, is about 90° , which is greater than the quotient which is obtained by dividing 360° by the number of web-sections. These sharp changes in angle assist in stretching the filaments on the drum, so as to leave little or no residual stretch in said filaments, in the final web.

I claim:

1. In combination, a rotatable drum having circumferential rows of pins, each circumferential row being spaced from the adjacent circumferential row in a direction parallel to the axis of rotation of said drum, movable feeding means adapted to feed material into the spaces between

said circumferential rows of pins, mechanism adapted to rotate said drum at a peripheral speed which exceeds the feeding speed of said feeding means.

2. Mechanism for spirally winding a web of material under tension, comprising a rotatable drum, feeding means located anterior said drum and operative to feed material which is to be wound on said drum to form said web under tension on said drum, the periphery of said drum having a series of recesses in which said web is located during said winding of said web, each said recess having a front end and a rear end, the depth of each recess increasingly progressively from its front end to its rear end, the rear end of each recess being located at the front end of the next adjacent recess to provide a sharp change in contour at the junction between the rear end of each recess and the front end of the next adjacent recess, each said rear end having forwardly projecting pins which engage and hold the respective part of the web against said rear end to provide a sharp change in angle in said web at each said junction; said pins being of

sufficient length to hold the web against said periphery forwardly of the tips of said pins and to maintain the part of the web which is directly engaged by said pins in thicker formation than forwardly of said pins in the respective recess.

3. A method of forming a web of material which consists of separate filaments, on the periphery of a rotatable drum, which consists in feeding said material to said periphery while maintaining said material under tension anterior said drum, continuously subjecting said filaments to tension while spirally winding said web in a series of layers around the periphery of said drum, locating said web on said periphery in the form of a series of consecutive sections during said winding operation, each section being maintained in a layer of greater thickness at its rear end than at its front end during said winding operation, the angle between the adjacent ends of consecutive sections being maintained in excess of an angle which is equal to 360° divided by the number of said sections.

BENJAMIN F. McCREERY.
